UNITED STATES PATENT OFFICE.

ELIJAH C. BARTON, OF EAST HAMPTON, CONNECTICUT.

DOOR-PLATE.

SPECIFICATION forming part of Letters Patent No. 332,775, dated December 22, 1885.

Application filed July 23, 1885. Serial No. 172,444. (No model.)

To all whom it may concern:

Be it known that I, ELIJAH C. BARTON, of 5
East Hampton, in the county of Middlesex
and State of Connecticut, have invented cer-
tain new and useful Improvements in Door-
Plates, of which the following is a descrip-
tion, reference being had to the accompan-
ying drawings, where—

Figure 1 is a front view of a door-plate em-
bodying my invention. Fig. 2 is a rear view
of the same with parts broken away to show
construction. The clamp-plate is shown on
the right as extending in dotted outline. Fig.
3 is a view in cross-section through the plate,
backing, and clamp, and in side view of a let-
ter-block on plane denoted by line X X of
Fig. 1. Fig. 4 is a detail sectional view of a
part of the plate on line Y Y of Fig. 2.

The object of my invention is to provide a
20 door-plate in which the letters making up any
name may be easily arranged and secured;
and to this end it consists in a frame-like
plate with an opening through it for the dis-
play of the faces of the removable letter-
25 blocks, in combination with the letter-block
and the clamp for holding them, as more par-
ticularly hereinafter described and claimed.

In the accompanying drawings, the letter
A denotes a door or name plate, preferably of
30 metal, cast to shape with the central opening,
A', through the plate, and the recess A² in
the back of it for the reception of the letter-
block B and the clamp C, so as to leave a flat
35 or plane back for contact with the door or
other surface to which the plate is adapted
to be fastened. This plate may be made in
any desirable shape and of any material, but
is preferably of a metal that is capable of high
40 polish or elaborate ornamentation in casting
to shape and finishing; and one advantage of
my construction is that when the plate be-
comes tarnished, as by wear, the letters can
be easily removed, the plate repolished, and
45 the letters replaced without having been soiled
by the cleaning of the plate. The blocks are
preferably of metal, and bear any desirable
form of letter, flush, sunk, or raised, and of
any desired style of type, with a background
50 suitable to the design of the plate. These
letter-blocks are enough higher than the open-
ing through the plate (see Fig. 3) to enable
the plate to overlap on top and bottom the
blocks which are placed side by side in the

plate in the order necessary to spell out any
given name, and along the back of the blocks 55
is placed a backing of some soft material, as
thick cloth, felt, or leather, with a clamping-
plate, C, back of that, and having in each
end slots C², each deep enough to allow the
60 plate to be moved endwise for the purpose of
engaging or disengaging either end of it from
below the broadened head of the studs C³, that
project from the back of the plate near each
end of the opening in it. The object of the
65 backing is to enable the several blocks to be
all held in place with a firm and practically
uniform pressure from the single clamping-
plate, irrespective of any slight irregularities
in the thickness of the blocks or surface of
70 the back of the plate on which they rest.

The plate is provided with screw-holes, or
bears bolts or like means for attaching it to
a door or other surface.

By means of my within-described invention
a name-plate may be quickly provided, 75
of any desirable grade as to quality and cost,
and after use with one name the same plate
may be fitted with another name, or the same
name replaced with letters of a different style
80 and at a slight cost, and in its simplest and
cheapest form the plate is of comparatively
slight cost.

I claim as my invention—

1. The combination, with the recessed name-
plate having an opening for the display of 85
letters, and adapted to be secured to a door
or other surface, of the series of removable
letter-blocks, an elastic backing for said let-
ter-blocks, and a clamping bar or plate se-
cured to the name-plate upon said elastic 90
backing by means of studs or screws, sub-
stantially as described, the said letters and
their securing devices all being within the
recess and below the plane of the rear edge of
the name-plate.

2. In combination, a door-plate, A, having
the opening A' and the recess A², and bearing
the studs C³ with broadened ends, the removable
letter-blocks B, and the clamping-plate
C, with slots C² in the ends, all substantially 100
as described.

ELIJAH C. BARTON.
